UNITED STATES PATENT OFFICE.

WILLIAM H. BROWN, OF PHILADELPHIA, AND WILLIAM C. BRINTON, JR., OF KENNETT SQUARE, PENNSYLVANIA, ASSIGNEES TO PHILIPS-BRINTON COMPANY, OF KENNETT SQUARE, PENNSYLVANIA, A CORPORATION OF PENNSYLVANIA.

CONTACT MAKER AND INTERRUPTER FOR IGNITION SYSTEMS.

1,234,278.

Specification of Letters Patent. Patented July 24, 1917.

Application filed July 6, 1915. Serial No. 38,225.

To all whom it may concern:

Be it known that we, WILLIAM H. BROWN and WILLIAM C. BRINTON, Jr., citizens of the United States, residing, respectively, at Philadelphia, county of Philadelphia, and State of Pennsylvania, and Kennett Square, Chester Co., Pennsylvania, have invented a new and useful Improvement in Contact Makers and Interrupters for Ignition Systems, of which the following is a full, clear, and exact description, reference being had to the accompanying drawings, which form a part of this specification.

The object of our invention is to provide an improved means for opening and closing the primary circuit in a single spark ignition system for automobiles. In such a system it is necessary that the circuit should be closed with certainty, but only momentarily in order to avoid a quick jump in amperage. It is also necessary that the contact should be made with the desired certainty and regularity under all the widely varying conditions arising in use. Thus the device must be operative, with equal certainty and effectiveness, with engines provided with any number of cylinders and under conditions, with any given engine, of maximum, minimum, and all intermediate speeds.

It is obviously desirable, if possible, to accomplish the required results by causing the circuit-closing member to positively effect contact by actuation from the cam- or timer-shaft. This has been so difficult of accomplishment that the most generally used type of contact device operates by advancing a movable member positively and providing a spring which, upon the release of said member, returns the same and thereby actuates the contact member to make and break the circuit. An example of such a device is found in the Kent Patent, No. 978,030, dated December 6, 1910.

It has, however, been found entirely practicable to positively actuate the contact member to make contact by positively advancing a primary member which, in turn positively moves the contact member into circuit-closing position and immediately thereafter causing the primary member to pass beyond the contact member and returning both members by a spring or

springs, the parts being so arranged that the primary member, on its return movement, will be inoperative to actuate the contact member to close the circuit. Such devices are set forth in the Brinton Patents, Nos. 1,129,445 and 1,129,446, dated February 23, 1915, and in the Brinton application, Serial No. 41,665, filed July 24, 1915, which, although filed as of a later date than this application, antedates our invention.

Heretofore, however, it has been found impossible to actuate the circuit closing member directly and positively by a part moving with the timer-shaft to effect only a momentary closing of the circuit with a small current consumption. That is, while it is a comparatively simple matter to arrange a shaft, a movable contact and a fixed contact in such relation that the shaft in its rotation will cause the first contact to move against the second contact to close a circuit, no natural and obvious arrangement of such elements will respond to the requirements of actual use.

In our invention, however, we have succeeded in so constructing and arranging said elements that they will operate to effect proper closure of the circuit with absolute certainty and regularity at all required speeds. In fact, owing apparently to the great simplification of construction which our invention effects, the maximum number of proper and effective circuit interruptions per second which may be produced has not been determined by the most severe tests.

A preferred embodiment of our invention is shown in the accompanying drawings, in which—

Figure 1 is a plan view with the cap removed.

Fig. 2 is a cross section.

Fig. 3 is a section on the line 3-3 of Fig. 1.

Fig. 4 is an enlarged sectional view of one of the contacts.

The cam-shaft or time-shaft *a* extends up through a base *b* (which may be made hollow to inclose a condenser chamber) and carries a head *c* of insulating material to which is secured the distributor conductor plate *d*. A cap *e* of insulating material fits upon the base *b* and incloses the top of shaft *a*, the head *c* and the contact device herein-

after described. The cap *e* carries the common terminal post *f* and the binding posts 1, 2, etc.; the secondary current being closed successively through the several binding 5 posts as the shaft *a* revolves, in a manner well known in the art.

Secured to and forming part of the shaft *a* is a disk *g* having a periphery shaped, as shown in Fig. 1, to provide a number of 10 cams or teeth *h* (corresponding, say, to the number of cylinders comprised in the engine). Each cam is shaped so that it will contact with the contact member hereinafter described only throughout a relatively 15 small part of the distance between corresponding parts of adjacent cams and so that it will move said member away from the axis of the shaft during the period of contact between said member and cam. Beyond 20 the high point of the cam it is cut away abruptly to allow of the instant return of said member by an actuating spring.

The contact member *i* is shown as a bar which is slideable between two flat faces 25 formed by the hooked end of a plate *j* projecting from a block *k* secured to the base *b*. The bar *i* is slotted at *m*, there being a projection *n* bent downwardly from one edge of the plate *j* and engaging said slot. 30 As the shaft *a* revolves in the direction of the arrow, it necessarily imparts a longitudinal movement to the bar *i*, the bar being guided in such movement by the bend connecting the upper and lower sections of the 35 plate *j*.

The outer end of the bar *i* is bent up and is provided with a contact nose *i'* facing in the direction of extension of the bar. Immediately beyond the nose is the end of a 40 contact pin *o*. This pin has a shoulder *p* which closes the open end of a hollow holder *r* having a head *s*. Between the head *s* and the shoulder *p* the pin *e* is of relatively small diameter and is surrounded by a coil 45 spring *t*, which normally holds the contact end of the pin at a definite distance from the nose of the contact bar *i*.

The holder *r* is threaded in a bracket *u*, which is secured to a block *v* of insulating 50 material.

It will be observed while the bar *i* is capable of swinging in one direction on the projection *n* as a pivot, it cannot swing in the opposite direction. That is, under the 55 impulse of the cams, when the shaft is rotating forward in the direction of the arrow, Fig. 1, the bar *i* cannot swing but can only move forward longitudinally. But if the shaft is turned in the reverse direction the 60 cams engage one longitudinal edge of the bar, thereby swinging it on the projection *n* as a pivot, whereby no contact will be made between bar *i* and pin *o*. When the shaft is rotating in a forward direction each cam 65 will move the bar *i* outward a distance some-

what greater than the space between the bar *i* and pin *o*, the result being that the bar will first strike the pin and then move it slightly against the tension of the spring *t*, thereby affording a measurable and accurately adjustable and determinable duration of contact. As soon as the high point of the cam rides beyond the bar *i*, the latter is returned to normal position by a spring *z*, which connects the upwardly turned part of the bar *i* with an upturned ear on the edge of the plate *j* nearest the shaft *a*. At the same time the spring *t* returns the pin *o* to normal position.

The washer *y*, on the outer end of pin *o*, 80 limits the movement of the pin in the direction of the contact bar.

Having now fully described our invention, what we claim and desire to protect by Letters Patent is:—

1. A contact maker and interrupter comprising a contact forming one terminal of a circuit, a contact bar forming the other terminal of the circuit and movable longitudinally toward and into direct engagement with the first contact, a spring yieldingly restraining the contact bar from longitudinal movement, and a rotatable member adapted in its rotation to directly engage said contact bar and move it longitudinally and thereby close the circuit through said contacts.

2. A contact maker and interrupter comprising a contact forming one terminal of a circuit, a contact bar forming the other terminal of the circuit and movable longitudinally toward and into direct engagement with the first contact, a spring yieldingly restraining the contact bar from longitudinal movement, a shaft whose axis is perpendicular to the direction of movement of said contact bar, and a cam on the shaft adapted in its rotation to directly engage said contact bar and move it longitudinally and thereby close the circuit through said contacts.

3. A contact maker and interrupter comprising a contact movable under tension in one direction, a co-operating contact movable under tension in the same direction and also pivotally movable under tension, and a cam rotatable on an axis perpendicular to the common direction of movement of such contacts and adapted when traveling in one direction to directly engage the second contact in said common direction to effect direct engagement between said contacts and when traveling in the other direction to swing the second contact on its pivot.

4. A contact maker and interrupter comprising a contact bar movable longitudinally and also pivotally movable in one direction from its normal position, a rotatable member adapted in one direction of movement to directly engage said bar and slide it longitudinally and in the other direction

of movement to swing said bar pivotally, and a contact adapted, in the sliding movement of the contact bar, to be directly engaged thereby to close the circuit.

5. A contact maker and interrupter comprising a contact bar movable longitudinally and also pivotally movable in one direction from its normal position, a rotatable member adapted in one direction of movement to engage said bar and slide it longitudinally and in the other direction of movement to swing said bar pivotally, a contact movable in the direction of movement of the contact bar and adapted in the sliding movement of the contact bar to be engaged and moved thereby to close and maintain closed the circuit, and a spring adapted, in said movement of said contact, to be compressed and to return said contact to normal position after the retraction of the contact bar.

6. A contact maker and interrupter comprising a contact bar movable longitudinally and also pivotally movable in one direction from its normal position, a rotatable member adapted in one direction of movement to engage said bar and slide it longitudinally and in the other direction of movement to swing said bar pivotally, a contact adapted, in the sliding movement of the contact bar, to be engaged thereby to close the circuit, and a spring adapted to return the contact bar to normal position when slid or swung away therefrom.

7. A contact maker and interrupter comprising a shaft, a contact, a contact bar slideable into engagement with said contact and also pivotally movable, a guide for the contact bar preventing the same from swinging on its pivot in one direction, and a cam on the shaft adapted when rotated in one direction to engage the contact bar and slide it along the guide and when rotated in the opposite direction to swing the contact bar on its pivot.

45. 8. A contact maker and interrupter, comprising a contact, a contact bar slideable into engagement with said contact and also pivotally movable in one direction from its normal position but restrained from pivotal movement in the other direction, a shaft, a cam thereon having a sloping face and an abrupt face, the sloping face of said cam, in the movement of the shaft on one direction adapted to engage the end of the contact bar near one corner thereof and slide the same into engagement with said contact, and, in the movement of the shaft in the opposite direction, adapted to engage the side edge of the contact bar near said corner and swing the same pivotally, and a spring adapted to return the contact bar to normal position after said cam in its movement in either direction clears said contact bar.

9. A contact maker and interrupter comprising a contact, a coöperating contact

member having a differential movement and adapted in one movement to directly engage said contact, and a rotatable member adapted in its movement in opposite directions to directly engage the contact member and impart to it one or the other of its movements dependent upon the direction of rotation of the rotatable member.

10. A contact maker and interrupter comprising a contact forming one terminal of the circuit, a slideable and pivotally movable contact member forming another terminal of the circuit and adapted in its sliding movement to directly and momentarily engage said contact, and a rotatable member adapted in its rotation in opposite directions to directly impart to the contact member its sliding and pivotal movements respectively.

11. A contact maker and interrupter comprising a yielding contact forming one terminal of the circuit, a contact member movable both slideably and pivotally, a spring normally holding the contact member from movement, and a rotatable member adapted in its movement in one direction to engage the end of the contact member, push it into circuit closing engagement with the yielding contact and then slide off the corner of the contact member, and adapted in its movement in the opposite direction to engage the side of the contact member and swing it on its pivot and then slide off the corner thereof.

12. A contact maker and interrupter comprising a contact forming one terminal of the circuit and slideable in a right line and restrained from movement otherwise, a co-operating contact member having a differential movement and adapted in one movement to directly engage said contact, and a rotatable member adapted in its movement in opposite directions to directly engage the contact member and impart to it one or the other of its movements dependent upon the direction of rotation of the rotatable member.

13. A contact maker and interrupter comprising a contact forming one terminal of the circuit and slideable in a right line and restrained from movement otherwise, a co-operating contact member having a sliding movement in a right line parallel to that of the contact and having also a swinging movement, and a rotatable member adapted in its movement in opposite directions to directly engage the contact member and impart to it one or the other of its movements dependent upon the direction of rotation of the rotatable member.

14. A contact maker and interrupter comprising a contact forming one terminal of the circuit, a contact member forming another terminal of the circuit, said contacts both being slideable along a common axis, and a rotatable member adapted to engage

the contact member at one side of said axis and push it into direct and momentary engagement with said contact.

15. A contact maker and interrupter comprising a contact forming one terminal of the circuit, a contact member forming another terminal of the circuit, said contacts both being slidable along a common axis, and a rotatable member whose axis is perpendicular to the axis along which said contacts slide and which is adapted in its rotation to directly engage the contact member and slide it into engagement with said contact, said axes extending in parallel planes spaced apart.

16. A contact maker and interrupter comprising a contact forming one terminal of the circuit, a contact forming another ter-

20 minal of the circuit and having a flat cam-engaging end, a spring to retract the contact member from the contact, and a rotatable member comprising a cam having a sloping face adapted to directly engage the flat end of the contact member and move it into circuit closing engagement with said contact, said cam having an abrupt drop 25 adapted, as the apex of the cam slides off the edge of the flat face, to allow the spring to instantly retract the contact member from the contact.

25 In testimony of which invention, we have hereunto set our hands, at Philadelphia, on this 3rd day of July, 1915.

30 WILLIAM H. BROWN.
